UNITED STATES PATENT OFFICE.

HENRY L. HASKELL, OF LUDINGTON, MICHIGAN, ASSIGNOR TO CARROM-
ARCHARENA COMPANY, OF LUDINGTON, MICHIGAN.

BILLIARD OR POOL TABLE.

No. 853,635.

Specification of Letters Patent.

Patented May 14, 1907.

Application filed March 9, 1903. Serial No. 146,969.

To all whom it may concern:

Be it known that I, HENRY L. HASKELL, a citizen of the United States, residing at the city of Ludington, in the county of Mason and State of Michigan, have invented certain new and useful Improvements in Billiard or Pool Tables, of which the following is a specification.

This invention relates to improvements in pool or billiard tables, and the like.

The objects of this invention are to provide an improved ball supporting rack for pool or billiard tables.

Further objects, and objects relating to the details of construction will definitely appear from the detailed description to follow.

I accomplish the objects of my invention by the devices and means described in the following specification.

The invention is clearly defined and pointed out in the claims.

A structure embodying the features of my invention is fully illustrated in the accompanying drawing forming a part of this specification, in which—

Figure 1 is a detail sectional view of a structure embodying the features of my invention taken on lines 1—1 of Fig. 2. Fig. 2 is a detail side elevation view of my improved ball supporting rack. Fig. 3 is an inverted detail view of my improved ball supporting rack.

In the drawing, the sectional views are taken looking in the direction of the little arrows at the ends of the section lines, and similar letters of reference refer to similar parts throughout the several views.

Referring to the lettered parts of the drawing, the supporting frame A for the bed of the table may be of the usual, or any desired, construction. To the frame A, I secure a ball holder B. This ball holder consists of a rod bent into a bail-like form which is slidably secured to the under side of the frame A by staples C so that it may be moved outwardly when it is desired to use the same, and form, in conjunction with the frame A, a secure support for the balls,—see Figs. 1 and 2.

The ends of the support B are bent upwardly at d to engage the notches d' toward the rear edge of the frame,—see Figs. 2 and 3, when the support B is in its outer position.

The frame is beveled at e so that the stop is guided into the notch. This retains the sup-

port B in position so that the same is not likely to be accidentally disengaged. When not in use, the support B may be moved back under the frame. This is accomplished by the slight upward lift which disengages the lugs d from the notches d' when the support may be pushed under the frame. The rod B is notched at c on its under sides to engage on the staples C to limit the backward movement of the rod.

It is evident that the rod B may be enameled, nickelated, ornamented as may be desired. It forms a very neat and satisfactory ball holder, and one that is very economical to produce. I preferably provide one for each side of the table for convenience in use.

I have illustrated and described my improved ball support in the form preferred by me on account of the economy in manufacture and convenience in use. I am aware, however, that it is capable of very considerable variation in structural details without departing from my invention.

Having thus described my invention, what I claim as new and desire to secure by Letters Patent, is—

1. The combination with a table bed of a downwardly projecting frame beneath the same; a bail-like rod B slidably secured to the under side of said frame by staples C; notches d' on the under side of said frame toward the rear edge; upturned lugs d on said rod B adapted to engage said notches, when said rod is in its operative position; and notches c in the under side of said rod, adapted to engage said staples when said rod is in its inner position, for the purpose specified.

2. The combination with a table bed of a downwardly projecting frame beneath the same; a bail-like rod B slidably secured to the under side of said frame by staples C; notches d' on the under side of said frame toward the rear edge; upturned lugs d on said rod B adapted to engage said notches, when said rod is in its operative position, for the purpose specified.

3. The combination with a suitable bed of a supporting frame therefor; a bail-like rod slidably secured to the under side of said frame, coacting when in its operative position with the side of said frame to form a ball support; and a suitable stop for said rod, for the purpose specified.

4. The combination with a suitable bed of

a supporting frame therefor; and a bail-like rod slidably secured to the under side of said frame, coacting when in its operative position with the side of said frame to form a ball support, for the purpose specified.

5. In a billiard table, the combination of a suitable bed; a supporting frame therefor; a bail-like rod arranged to be collapsed beneath said frame, coacting when in its operative position with the side of said frame to

form a ball support, for the purpose specified.

In witness whereof, I have hereunto set my hand and seal in the presence of two witnesses.

HENRY L. HASKELL. [L. s.]
